ABSTRACT OF THE DISCLOSURE

A support member for a missile launching and guiding device is formed of an h-shaped bracket made of a light-weight material such as a plastic. The bracket extends longitudinally in the firing direction of the device and supports a housing in its forward end containing the means for launching and guiding the missile. At its rear end the bracket supports a coupling member for securing the missile and its launching tube to the device.

SUMMARY OF THE INVENTION

The invention is directed to a device for launching and guiding missiles from a launching tube and, more particularly, it is directed to a support bracket arranged to support the coupling member which secures the launching tube to the device. Further, the support bracket is arranged to support a housing containing the means for launching and guiding the missile. In addition, a sighting member is mounted on the bracket for aiming and guiding the missile.

Such launching and guiding devices are adjustable in the elevating and traversing directions for properly aiming and guiding missiles. The launching and guiding device of the present invention comprises a stand and tripod which can be detachably locked to the bracket supporting the launching tube and the sight. Such a missile firing weapon is characterized by its versatility. It can be carried and operated by a single individual, it can be operated supported on the ground or, after disengagement from its stand, it can be operated from the shoulder in the standing, kneeling or prone positions.

Since the missile firing weapon is intended to be handled by a single individual, its weight and the simplicity of the mechanisms contributing to its makeup are of paramount importance.

Accordingly, it is the primary object of the invention to simplify the arrangement and operation of a missile launching device, particularly in the construction of the member used both for supporting its guiding and launching means and for supporting the launching tube for the missile.

Another object of the invention is to provide a light-weight construction for a bracket member affording the support both for the missile launching tube and for the housing containing the means for launching and guiding missiles.

A further object of the invention is to supply a configuration for the bracket which provides a protective shield for the person operating the missile launching device.

Moreover, another object of the invention is to shape the bracket to receive the missile launching tube in interlocking engagement. Further, means are formed in the bracket for guiding the missile launching tube and its coupling member into interlocking engagement.

Therefore, the present invention provides a bracket for a missile launching and guiding device in which the

2

bracket is arranged to support both a housing containing the missile launching and guiding system and a missile launching package or assembly. The device is adjustable in the elevating and traversing directions and it contains a sighting member, mounted on the bracket, for aiming, tracking and guiding the missile. To afford a compact lightweight construction, the bracket is formed of a plastic shell construction having a substantially h-shaped cross section. Disposed in one end of the bracket, in a box-type housing support, is the electric and electronic means for launching and guiding the missile.

Since a plastic shell construction is employed for the bracket, the weight of the entire launching guiding device is considerably reduced and it is much easier to transport, especially since the weapon is intended to be carried by a single individual. The housing support for the electronic means is arranged in the center of gravity range of the bracket, whereby the forces acting on the bracket are transmitted into the housing support and the plastic shell construction of the bracket, is relieved, to a considerable extent, of the forces developed in the launching operation. The box-type housing support contains all of the electric and electronic parts required for launching and guiding the missile. In this way, the entire system used in launching and guiding the missile is centrally disposed and can be checked and maintained in a simple and easy manner. Further, if it is necessary to do so because of its location in the bracket, the contacts of the housing support can be easily removed and repaired as a self-contained unit. Because of the nature of its contents, the housing is provided with an opening or door which is closed in a gas-tight manner.

An important feature of the bracket is the formation, in its rear portion, of a U-shaped recess for receiving the coupling member which attaches the missile launching tube to the device. Moreover, the forward portion of the bracket has a U-shaped section formed by the lower part of its h-shaped configuration which is open at the bottom and receives the support housing containing the means for launching and guiding the missile.

In view of the configuration of the bracket and of the rigid lightweight structure afforded by its plastic shell construction, the bracket affords simple handling of the launching and guiding device, particularly in attaching the missile launching package, composed of the coupling member, the launching tube and the missile, into the bracket. Within the U-shaped recess at the rear part of the bracket, sliding guides are provided for directing the coupling member and its attached launching tube in correct alignment into the launching and guiding device. An electric plug connection is provided on the forward end of the coupling member which is secured and properly guided into a mating electric plug connection formed in the bracket and connected to the housing support for completing all of the electrical connections necessary between the missile and the launching and the guiding device. This arrangement ensures a rapid and safe connection of the missile launching package into the launching and guiding device.

For ease in aiming and guiding the missile, a pair of handles are arranged on the opposite sides of the forward end of the bracket, and are of special advantage when firing from the shoulder or a similar position. Preferably, the handles are shaped so that one portion conforms to the thumb and the remaining portion conforms to the finger and hand of the person operating the missile device. The construction provided is particularly rugged for withstanding the rough treatment such weapons experience in use. Further, because the handles are closely fitted to the bracket, they do not interfere with its operation and are particularly effective in aiming, tracking and guiding the missiles.

Another feature of the invention is the manner in which the sight is rigidly connected to the bracket. The sighting member is arranged so that a portion of it bears on or is supported by the housing support. The sighting member is aligned on the bracket whereby the launching axis of the missile is displaced in the elevating and traversing direction with respect to the optical axis of the sight. Since the sighting member is fastened, at least in part, to the housing support, the forces acting on it are absorbed for the most part by the housing support and the shell construction of the bracket is relieved of these stresses. The optical axis of the sight is slightly displaced with respect to the launching axis of the missile in order to compensate for the moments developed during the take-off of the missile. This arrangement insures the ability of the guiding device to pick up the missile within the narrow range of its position finder which is contained within the sighting member.

The unbalancing moments which are developed as the missile is fired or launched are due mainly to the gravity component which is not fully compensated by the lifting forces produced at the start of the acceleration phase. This unbalancing effect causes the missile to drop a certain amount immediately after it leaves the launching tube. Further, it also results in a force acting transverse to the launching direction of the missile which is effected by the break-off of the guide wire cemented to the skin of the launching tube and occurs immediately after the missile ejects from the tube.

In order to balance these various moments developed as each of the missiles is fired, the launching axis of the missile is adjusted by several degrees in the launching direction with respect to the optical axis of the sight in order to displace the unbalancing moments produced by gravity by several degrees to the right to take care of the lateral interference caused by the break-off of the guide wire.

Finally, in the present arrangement care is taken that the points of attachment between the sighting member and the device are approximately in the center of gravity whereby there is little likelihood of change in the direction of sight caused by the weight reduction occurring as a missile is launched.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWINGS

In the drawings:

FIG. 1 is a perspective view of the parts forming the launching and guiding device in a separated arrangement and including a bracket embodying the present invention;

FIG. 2 is a front end view of the launching device shown in FIG. 1 in its assembled arrangement;

FIG. 3 is a rear end view of the launching and guiding device shown in FIG. 1; and

FIG. 4 is a top view, partly sectioned, of the rear portion of the bracket of the launching and guiding device illustrated in FIG. 1.

DETAILED DESCRIPTION OF THE PREFERRED EMBODIMENT

In FIG. 1, a missile launching and guiding device is shown in a separated arrangement and it is comprised of a stand 2 on which a bracket 3 is supported and in turn the bracket provides a mounting for the launching tube 4. The stand 2 is provided with means for adjustably positioning the device in the elevating and traversing directions. On the stand, a first gear 8, 9 is positioned for traversing movement of the device and a second gear 5 is

provided for movement in the elevating direction which can be accomplished by an operator handling the rotary handle 6.

In FIG. 1 it will be noted that the bracket 3 extends in the direction of the launching tube, that is in the firing direction of the device, and FIGS. 2 and 3 disclose the cross sectional shape of the bracket in the direction transverse to its longitudinal axis. The bracket has an h-shaped cross section having a lower portion with a U-shaped construction with the opening facing downwardly and an upwardly extending leg which provides a shield 11, see FIG. 1, for the protection of the person operating the missile device. At its rear portion, as viewed in the firing direction, the bracket 3 in addition to its U-shaped portion facing downwardly is provided with a recess 12 also having a generally U-shaped configuration open at the top. The recess 12 is arranged to receive a coupling element 13 for securing the launching tube 4 to the device.

At the forward part of the bracket 3, as shown in FIG. 2, within its downwardly directed U-shaped section 14 there is positioned a housing support designed in a box-type form. The bracket 3 is attached to the stand 2 through the fastening points 15 of the housing 10. Handles 16 and 17 for effecting the traversing movement are mounted on the sides of the bracket 3 at the forward end of the support housing 10.

Bracket 3 is formed of a plastic shell construction and is comprised of at least two glass fiber-reinforced plastic shells with the space in between them containing a foam such as made from polyurethane.

Mounted on the opposite side of the bracket 3 from the launching tube 4 is a sighting member 18 for picking up and locating the target. This sighting member also contains the position finder required for tracking the missile. The sighting member 18 is secured through a connection 20 to the housing 10 which transmits the major portion of the forces caused by the weight of the sighting member to the housing. With the sighting member 18 supported by the housing, its plastic shell construction is relieved, to a great extent, of the forces acting on or through it.

The missile launching package is comprised of the launching tube 4 containing a missile and the coupling element 13 which secures the package or assembly to the bracket 3. During storage and transportation the coupling member 13 is rigidly attached to the launching tube 4 and to the missile. Located in the forward end of the coupling element 13, as viewed in the firing direction of the device, is a plug connection 21 arranged to engage a mating plug connection 22 rigidly attached to the rearward end of the housing 10. The electric plug connection between the coupling member 13 and the housing 10 is designed to transmit the forces developed in the launching operation from the launching tube 4 to the housing 10. For properly aligning the coupling member 13 in the recess 12, the bracket 3 contains a pair of sliding guides 23 which engage corresponding grooves formed in the coupling element. In the forward portion of the recess 12, a pair of guide ribs 30 are provided immediately behind the plug connection 21 for leading the plug connection on the coupling element into the mating plug connection 22 in the housing support 10. In addition, an upwardly extending locking knob 24 is provided in the recess 12 for engagement within a corresponding recess 25 in the coupling element for locking the coupling element in place within the bracket.

At the forward and rearward ends of the coupling member and the launching tube, separation surfaces 26 are provided which afford a substantially friction-free detachment of the launching tube from the coupling after the missile is launched from the tube. As the missile is launched, the firing tube is detached from the coupling member in the rearward direction, that is opposite to the firing direction.

The support housing 10 has a box-like shape and contains the electrical parts necessary for firing, tracking,

and guiding the missile. Prior to launching, the missile 19, see FIG. 2, is electrically connected to the launching and guiding device through the plug connections 21, 22, and during its guided flight it is connected by means of a guidewire 31, note FIG. 1.

For maintenance and repair, access to the electrical and electronic means disposed within the housing 10 can be achieved through the opening 29. This opening is of a gas-tight type, since the entire unit is maintained, for safety reasons, in a protective gas atmosphere within the housing 10.

At its front end, the bracket 3 is provided with a bearing surface 27 which permits the launching and guiding device to be supported on a natural or artificial abutment or support surface if the latter is to be operated in a standing or kneeling position without the use of the tripod on the stand.

At its rear end, the sight bracket 3 is designed to afford a supporting surface 28 which permits the launching device to be operated from the shoulder of the individual operating the weapon.

Secured to the opposite sides of the bracket 3 at its forward end are a pair of handles 16 and 17. As shown by the handle 16 in FIG. 1, both of the handles are shaped to conform to the hand of the person operating the device. A limiting surface 161 of the handle conforms to the shape of the thumb and another limiting surface 162 conforms to the inner surface of a finger. Further, the sides 163 of the handles containing the recesses 164 conform to the ball of the hand. This design of the handles affords easy alignment of the support bracket 3 in the traversing direction and facilitates the sighting of the target and the tracking and guiding of the missile.

While the bracket has been described as constructed from a plastic shell arrangement, it will be appreciated that other materials may be used, for example a light metal construction, without departing from the invention.

While a specific embodiment of the invention has been shown and described in detail to illustrate the application of the inventive principles, it will be understood that the invention may be embodied otherwise without departing from such principles.

What is claimed is:

1. In a device for launching and guiding missiles arranged to be adjustably positioned in the elevating and traversing directions, a support member for releasably mounting a missile launching tube assembly on the device comprising a bracket having a general h-shaped section arranged to extend in the firing direction of the device, said bracket having a front end facing in the firing direction of the device and a rear end facing in the opposite direction, a first section of said bracket located at the front end thereof, and a second section located at the rear end of said bracket, a box-type housing support disposed in said first section of said bracket and having mounted therein means for firing, tracking and guiding the missile, said housing support being arranged approximately in the center of gravity of the bracket, and said second section of said bracket having means to receive a missile launching assembly in interengaged relationship.

2. In a device as set forth in claim 1, wherein a door is located in said housing support for gaining access to its interior, and said door arranged in gas-tight relationship with said housing.

3. In a device as set forth in claim 1, wherein said bracket is formed of a lightweight material.

4. In a device as set forth in claim 3, wherein said bracket is formed of a plastic shell construction comprising at least two such shells formed with glass fiber reinforcement and a polyurethane foam disposed between the plastic shells.

5. In a device as set forth in claim 1, wherein said bracket has a lower U-shaped portion with its opening facing downwardly and an upwardly directed leg secured to and extending upwardly from one side of said U-shaped portion, said leg arranged to form a protective shield extending along one side of the missile launching assembly, and said first and second sections of said bracket located in the U-shaped portion thereof.

6. In a device as set forth in claim 5, wherein said second section has a concave shaped recess in its upper surface which extends forwardly to said housing support located in said first section.

7. In a device as set forth in claim 6, wherein an electrical plug connection is disposed in the rearward end of said support housing and is arranged to receive a mating plug connection disposed in the forward end of the missile launching assembly.

8. In a device as set forth in claim 7, wherein a locking knob is provided in the concave-shaped recess of said second section of said bracket and is arranged to engage within a recess in the missile launching assembly.

9. In a device as set forth in claim 8, wherein sliding guides are provided in the rearward portion of said recess in said second section and are arranged to engage within grooves located in the missile launching assembly.

10. In a device as set forth in claim 9, wherein guide recesses are formed in the forward portion of said recess in said second section immediately rearward of said plug connection in said housing support for aligning and leading the missile launching assembly into said plug connection.

11. In a device as set forth in claim 1, wherein a sighting member is positioned on and is connected to the opposite side of said upwardly extending leg from said U-shaped portion, said sighting member is attached also to and its major support is provided by said housing support.

12. In a device as set forth in claim 1, wherein a pair of handles are mounted on the opposite sides of said support bracket at the forward end of said housing support.

13. In a device as set forth in claim 12, wherein said handles have a shape arranged to conform to the shape of the hands of a person operating the device and are fitted closely to said bracket to avoid any interference with the operation and transportation of the missile launching device.
